ABSTRACT OF THE DISCLOSURE

A system utilizing electron beam produced light diffraction deformations in a light modulating fluid for control of light passed through the system for projection of color images in accordance with the deformation without development of random deformations in the fluid. The physical and electrical parameters of the system, such as electron beam current, fluid layer depth and viscosity of modulating fluid are set in particular relationships to one another to achieve only the desired deformations in the fluid.

The present invention relates to improvements in apparatus and method for the projection of images of the kind including a viscous light modulating medium deformable into diffraction gratings by electron charge deposited thereon in accordance with electrical signals corresponding to the images.

In one of its particular aspects the invention relates to the projection of color images using a common area of the viscous light modulating medium and a common electron beam for the production of deformations in the medium for simultaneously controlling the transmission therethrough point by point of the primary color components, in kind and intensity, in a beam of light in response to a plurality of simultaneous occurring electrical signals, each deformation corresponding point by point to the intensity of a respective primary color component of an image to be projected by such beam of light. Such systems provide a number of advantages over conventional systems in which the resultant light output is dependent on the energy in an electron beam and is a small percentage of the limited energy available in an electron beam.

One such system for controlling the intensity of a beam of light includes a viscous light modulating medium which is adapted to deviate each portion of the beam in accordance with deformations in a respective point thereof on which the portion is incident, and a light mask having a plurality of apertures therein disposed to mask the beam of light in the absence of any deformation in the light modulating medium and to pass light in accordance with the deformations in said medium. The intensity of the portions of the beam of light deviated by the light modulating medium and passed through the apertures of the light mask varies in accordance with the magnitude of deformations produced in the light modulating medium.

The light modulating medium may be a thin light transmissive layer of fluid in which the electron beam forms phase diffraction gratings having adjacent valleys spaced apart by a predetermined distance. Each portion of light incident on a respective small area or point of the medium is deviated in a direction orthogonal to the direction of the valleys. The intensity of the deviated light is a function of the depth of the valleys.

The phase diffraction grating may be formed in the layer of fluid by the deposition thereon of electrical charges, for example, by a beam of electrons. The beam may be directed on the medium and deflected along the surface thereof in one direction at successively spaced intervals perpendicular or orthogonal to the one direction. Concurrently the rate of deflection in the one direc-

2

tion may be altered periodically at a frequency considerably higher than the frequency of scan to produce alterations in the electrical charges deposited on the medium along the direction of scan. The concentrations of electrical charge in corresponding parts of each line of scan form lines of electrical charge which are attracted to a suitably disposed oppositely charged transparent conducting plate on the other surface of the layer thereby producing a series of valleys therein. As the periodic variations in the period of scan are changed in amplitude, the depth of the valleys are correspondingly changed. Thus, with such a means each element of a beam of light impinging on one of the opposite surfaces of the layer is deflected orthogonally to the direction of the valleys or lines therein by an amount determined by the spacing between adjacent valleys, and the intensity of an element of deflected light is a function of the depth of such valleys.

When a beam of white light, which is constituted of primary color components of light, is directed on a diffraction grating, light impinging therefrom is dispersed into a series of spectra on each side of a line representing the direction or path of undeviated light. The first pair of spectra on each side of the undeviated path of light is referred to as first order diffraction pattern. The next 20 pair of spectra on each side of the undiffracted path is referred to as second order diffraction pattern, and so on. In each order of the complete spectrum the blue light is deviated the least, and the red light the most. The angle of deviation of red light in the first order light pattern, for example, is that angle measured with reference to the undeviated path at which the ratio of the wavelength of red light to the line to line spacings of the grating is equal to the sine of the deviation angle. The angle of deviation of the red light in the second order 30 pattern is that angle at which the ratio of twice the wavelength of red light to the line to line spacing of the grating is equal to the sine of the angle, and so on.

If the beam of light is oblong in shape, each of the spectra is constituted of color components which are 40 oblong in shape. If the diffracted light is directed onto a mask having a wide transparent slot appropriately located on the mask, the light passed through the slots is essentially reconstituted white light, each portion of which is of an intensity corresponding to the depth of the valleys illuminated by such portion. Such a system as described 50 would be suitable for the projection of television images in black and white. The line to line spacing of the grating formed in each part of the light modulating medium is the same and determines the deviation of light under conditions of modulation. The depth of the valleys formed in each part of the light modulating medium varies in accordance with the amplitude of the modulating signal and determines the intensity of light in each deviated portion of the beam.

Systems have been proposed for the projection of three primary colors by a common viscous light modulating medium in which light deviating deformations are produced therein by a common electron beam modulated in various ways to produce a set of three diffraction gratings 60 on the common media, each corresponding to a respective primary color component. The line to line spacing of each of the diffraction gratings are different thus producing a different angle of deviation for each of the primary color components. The depth of the deformation 65 is varied in accordance with a respective primary color signal to produce corresponding variations in the intensity of light in the first, second and higher diffraction orders. The apertures in a light output mask are of predetermined extent and at locations to selectively pass the desired 70 orders of primary color components of the diffraction spectrum. The line to line spacing of each of the three primary diffraction gratings determines the width and

location of the cooperating slot to pass the respective primary color component when a diffraction grating corresponding to that color component is formed in the light modulating medium.

In the kind of system under consideration an electron beam is modulated by a plurality of carrier waves of fixed and different frequency each corresponding to a respective color component, the amplitude of each of which is modulated in accordance with an electrical signal corresponding to the intensity of the respective color component to form a plurality of diffraction gratings having valleys extending in the same direction, each grating having a different line to line spacing corresponding to a respective primary color component and the valleys thereof having an amplitude varying in accordance with the intensity of a respective primary color component. If the primary color components selected are blue, green and red, and the carrier frequency associated with each of these colors is proportionately lower, the deviation in the first order spectrum of the blue component of white light by the blue diffraction grating, and similarly the deviation of the green component by the green diffraction grating, and the deviation of the red component by the red diffraction grating, can be made to correspond quite closely. Accordingly, a pair of transparent slots placed in the light mask in position, relative to the undeviated path of light, corresponding to that deviation and of just sufficient orthogonal extent, pass all of the primary components. The intensity of each of the primary color components in the beam of light emerging from the mask would vary in accordance with the amplitude of a respective electrical signal corresponding to the respective color component. Projection of such a beam reconstitutes in color the image corresponding to the electrical signals.

In a modification of the system described above and to be considered in detail herein, one set of grating lines is formed perpendicular or orthogonal to the other sets of grating lines. In such a system light filters and focussing elements direct red and blue light from a source of white light through the light modulating medium onto appropriate opaque and transparent portions of the light output mask cooperatively associated with the red and blue diffraction gratings formed in the light modulating medium to produce the desired operation explained above and direct green light from the source of white light on the common area of the light modulating medium and onto appropriate opaque and transparent portions in the light output mask which are cooperatively associated with the green diffraction grating formed in the light modulating medium. A single electron beam of substantially constant current is directed onto the light modulating medium and is deflected horizontally and vertically over the active area of the light modulating medium to form a raster thereon. The three diffraction gratings are formed on the raster area by appropriate modulation of the electron beam. The red and blue diffraction gratings are formed by appropriate velocity modulation of the electron beam in the direction of horizontal scan. The natural grating formed by the horizontal scan of the electron beam serves as the green diffraction grating.

Differential charge deposited by the electron beam produces a deformation in the light modulating medium. The deformation rises exponentially to a maximum and thereafter decays as the charge on the surface of the light modulating medium decays through conduction through the light modulating medium. The time it takes for the deformation to reach 63 percent of maximum value in response to a step force function is referred to as the mechanical time constant, and the time constant it takes for the electric force producing the deformation to decay to 63 percent of its peak value is referred to as the electrical time constant. For the successful operation of the system it is important that the sum of the mechanical and electrical time constant be of the order of the duration of a field of scan, i.e., the deformation should have decayed

to about one-third of its peak value by the time the electron beam is in a position to deposit another pattern of charge at that point.

Consider now an element of the raster representing a picture element. Consider portions of three diffraction gratings being formed on such portion. For good rendition of the color composition of such portion in a projected image it is important that in the absence of any video modulation of any one of the three color components that no grating be formed at any point in the light modulating medium and that no light be diffracted. As a grating is formed light should be diffracted and increased in intensity in accordance with the amplitude of the grating to a certain maximum value and that the variation from zero diffraction of light to full diffraction of light should be in a specific ratio, for example, 100 to 1 to provide good gradations in that color. Such variation may be thought of in terms of the average efficiency of the grating which is defined as the amount of light of a color component passed by the diffraction grating as a percent of the total light incident on that portion of the grating. For good color rendition not only should there be a good range from zero to maximum efficiency for each of the color components, but also the maximum average efficiency for each of the color components should be approximately the same to give the desired range of color composition in the projected image. Expressed in other words, the maximum deformation produced for each of the primary colors in response to the differential charge distribution produced by the corresponding modulations should be comparable, and the time of rise and fall of the deformations associated with each of the gratings as well as the average value of such deformations should be more or less comparable to provide balanced average light transmission efficiencies for the three primary colors.

It has been found that the mechanical time constant of a grating is a function principally of the viscosity of the light modulating fluid, the depth of the light modulating fluid layer, and the grating line spacing, and surface tension of the fluid. For high viscosity fluids the mechanical time constant is large and vice versa. For thin layers the mechanical time constant is large and vice versa. For large grating line spacing the mechanical time constant is large and vice versa. The mechanical time constant varies inversely as the fourth power of the grating line density when the line to line spacing of the grating is large in comparison to the depth of the light modulating medium. The electrical time constant is principally a function of the mode of conduction of charges through the fluid layer. The electrical time constant varies in a direct relationship with the product of viscosity and depth, and in an inverse relationship with electron beam current. It has also been found that mobility of charge carriers involved in the electrical decay of charge on the fluid varies in an inverse relation with the viscosity.

From the above considerations it is apparent that for the mechanical time constants of the deformations associated with each of the three diffraction gratings the factors of viscosity and depth are the same. However, the factor of grating spacing is different. Typically the difference in spacing between the grating of largest line to line spacing to the smallest line to line spacing may be of the order of 2 to 1, and in addition the ratio of the mechanical time constant thereof varies approximately as the fourth power of the density of such gratings, i.e., the mechanical time constant of the large line to line spacing grating is considerably larger than the mechanical time constant of the smallest line to line spacing grating. It is also noted that in the kind of system discussed wherein the depth is small in relation to the line to line spacing the electrical decay, i.e., the electrical time constant, is not a function of the line to line spacing and is substantially the same for all three gratings. Accordingly, if a value of mechanical time constant and appropriate electrical time constant is selected for the deformations

associated with the green diffraction grating to provide good average light transmission efficiency for green, the average light transmission efficiency of the red grating which may be the grating of the smallest line to line spacing would be poor due to the fact that the mechanical time constant associated with deformations of such gratings would be very short and consequently the deformations would arise rapidly and decay to a small value well prior to the termination of a field.

In patent application Ser. No. 419,475, filed Dec. 18, 1964 and assigned to the assignee of the present invention such problem is solved. The viscosity and depth of the layer are selected at which the mechanical time constant of the diffraction grating of large line to line spacing is such that it is substantially less than the electrical time constant thereof. The overall rise and decay time of such deformations is selected to be comparable to the period of a field. In such a system wherein the electrical time constant is of substantially larger time than the longest mechanical time constant of any of the gratings, the desired average efficiency of the grating is provided in deformations of all of the gratings. Such a requirement is met by a range of values of viscosity and thickness. The graph of a desired constant average light efficiency of the red diffraction grating which in the illustrative embodiment is selected to have the smallest line to line spacing plotted in terms of viscosity versus thickness shows that starting with a high viscosity for increasing thickness a decreasing viscosity would maintain such constant average efficiency. Similarly, a corresponding average efficiency graph for the green grating which in the illustrative embodiment is selected to have the largest line to line spacing plotted in terms of viscosity versus thickness shows that starting with low viscosity for an increasing thickness, the increasing viscosity would maintain a desired constant average efficiency. Depending on the constant average efficiencies desired pairs of values of thickness and viscosity exist which provide comparable average light efficiencies in the grating of largest line to line spacing and in the smallest line to line spacing. With proper balancing of the light transmission characteristics of the gratings of the smallest line to line spacing with the gratings of largest line to line spacing with regard to average light transmission, efficiency of the grating of intermediate line to line spacing would inherently be of a suitable value. In addition, a specific relationship between the mechanical time constant τ_m and the electrical time constant τ_e of the grating having lines parallel to the raster lines must be maintained to avoid other effects to be described in detail below.

From considerations such as the above it is apparent that relatively thick layers of light modulating fluid are necessary for uniformly good deformation or writing characteristics. However, we have found that when electron charge deposited in the manner indicated above on thick layers of fluid to produce desired deformation therein that, in addition, unwanted deformations bearing no relationship to the desired deformations are formed. The deformations are appreciable in depth in relationship to the desired deformations and substantial in extent. They produce deviation of light which deleteriously affects the contrasts in the projected image and in themselves they become a part of the projected image. The unwanted deformations are referred to as noise. Such unwanted deformations appear in the form of haziness or what is commonly referred to as snow in the projected image.

We have found that for a particular light modulating fluid if the thickness utilized in the system is reduced below a certain critical thickness that such unwanted deformations are rendered imperceptible. We also found that such critical thickness varies in an inverse relationship to the current of the electron beam, i.e., for smaller electron beam currents the critical thickness is larger.

The present invention is directed to the provision of a system and methods of operation thereof which enable good information writing qualities to be obtained in the

light modulating fluid as evidenced in one form by good and balanced efficiencies for grating densities of widely different values while at the same time avoiding unwanted perturbation on the surface of the light modulating medium which deleteriously affects the performance of the system. In carrying out the invention the physical parameters and electrical parameters of the system, and the physical properties of the light modulating fluid are provided which enable the aforementioned dual purposes in the light modulating medium to be obtained. Specifically in one exemplary form of the invention the thickness of the light modulating medium and the current of the electron beam are set in relationship to one another with appropriate regard to the viscosity of the medium to provide good writing qualities in the medium without the formation of unwanted perturbations or noise therein.

Accordingly, an object of the present invention is to provide an improved projection system using a viscous light modulating medium and methods of operation thereof.

It is also an object of the present invention to provide a light valve projection system of high sensitivity in which the projected image thereof is free of internally generated noise in the viscous light modulating medium.

It is also an object of the present invention to provide a color projection system utilizing a viscous light modulating medium on which are formed superimposed light diffraction deformations having widely differing line densities each corresponding to a respective color component of the system, of high performance with regard to excellent light transmission efficiency, control and balance of the color components and which is free of internally generated noise in the viscous light modulating medium.

The novel features believed to be characteristic of the invention are set forth in the appended claims. The invention itself, together with further objects and advantages thereof, may best be understood by the following description taken in connection with the following drawings in which:

FIGURE 1 is a schematic diagram of the optical and electrical elements of a system useful in explaining the present invention.

FIGURE 12 shows graphs of constant average light efficiency for the red grating and graphs of particular time constants for the green diffraction grating of the system of FIGURE 1 as plotted on coordinates of viscosity of light modulating fluid versus fluid layer depth useful in explaining aspects of the operation of the system in accordance with the present invention. On the same coordinates is plotted a graph of allowed values for a two to one cancellation ratio.

FIGURES 13 through 15 show graphs of critical thickness of light modulating fluid medium versus current density at raster area for various light modulating fluids.

Referring now to FIGURE 1 there is shown a simultaneous color projection system comprising an optical channel including a light modulating medium 10, and an electrical channel including an electron beam device 11, the electron beam 12 of which is coupled to the light modulating medium 10 in the optical channel. Light is applied from a source of light 13 through a plurality of beam forming and modifying elements onto the light modulating medium 10. In the electrical channel electrical signals varying in magnitude in accordance with the point by point variation in intensity of each of the three primary color constituents of an image to be projected are applied to the electron beam device 11 to modulate the beam thereof in the manner to be more fully described below, to produce deformations in the light modulating medium which modify the light transmitted by the modulating medium in point by point correspondence with the image to be projected. An apertured light mask and projection lens system 14, which may consist of a plurality of lens elements, on the light output side of the light modulating medium function to cooperate with the light modulating medium to control the light passed by the optical channel and also to project such light onto a screen 15 thereby reconstituting the light in the form of an image.

More particularly, on the light input side of the light modulating medium 10 are located the source of light 13 consisting of a pair of electrodes 20 and 21 between which is produced white light by the application of voltage therebetween from source 22, an elliptical reflector 25 positioned with the electrodes 20 and 21 located at the adjacent focus thereof, a generally circular filter member 26 having a vertically oriented central portion adapted to pass substantially only the red and blue, or magenta, components of white light and having segments on each side of the central portion adapted to pass only the green component of white light, a first lens plate member 27 of generally circular outline which consists of a plurality of lenticules stacked in a horizontal and vertical array, a second lens plate and input mask member 28 of generally circular outline also having a plurality of lenticules on one face thereof stacked in horizontal and vertical array, and the input mask on the other face thereof. The elliptical reflector 25 is located with respect to the light modulating medium 10 such that the latter appears at the other or remote focus thereof. The central portion of the input mask portion of member 28 includes a plurality of vertically extending slots between which are located a plurality of vertically extending bars. On the segments of the mask on each side of the central portion thereof are lo-

cated a plurality of horizontally oriented slots or light apertures spaced between similarly oriented parallel opaque bars. The first plate member 27 functions to convert effectively the single arc source 13 into a plurality of such sources corresponding in number to the number of lenticules on the lens plate member 27, and to image the arc source on individual separate elements of the transparent slots in the input mask portion of member 28. Each of the lenticules on the lens plate portion of member 28 images a corresponding lenticule on the first plate member onto the active area of the light modulating medium 10. With the arrangement described efficient utilization is made of light from the source, and also uniform distribution of light is produced on the light modulating medium. The filter member 26 is constituted of the portions indicated such that the red and blue light components from the source 13 register on the vertically extending slots of the input mask member 28, and green light from the source 13 is registered on the horizontal slots of the input mask member 28.

On the light output side of the light modulating medium are located a mask imaging lens system 30 which may consist of a plurality of lens elements, an output mask member 31 and a projection lens system 32. The output mask member 31 has a plurality of parallel vertically extending slots separated by a plurality of parallel vertically extending opaque bars in the central portion thereof. The output mask member 31 also has a plurality of horizontally extending slots separated by a plurality of parallel horizontally extending opaque bars in a pair of segments on each side of the central portion thereof. In the absence of deformations in the light modulating medium 10, the mask lens system 30 images light from each of the slots in the input mask member 28 onto corresponding opaque bars on the output mask member 31. When the light modulating medium 10 is deformed, light is deflected or deviated by the light modulating medium, passes through the slots in the output mask member 31, and is projected by the projection lens system 32 onto the screen 15. The details of the light input optics of the light valve projection system shown in FIGURE 1 are described in the aforementioned copending patent application Ser. No. 316,606, filed Oct. 16, 1963, and assigned to the assignee of the present invention.

The output mask lens system 30 comprises four lens elements which function to image light from the slots in the input mask onto corresponding portions of the output mask in the absence of any physical deformation in the light modulating medium. The projection lens system 32 in combination with the light mask lens system 31 comprises a composite lens system for imaging the light modulating medium on a distant screen on which an image is to be projected. The projection lens system 32 comprises five lens elements. The plurality of lenses are provided in the light mask and projection lens system to correct for the various aberrations in a single lens system. The details of the light mask and projection lens system are described in patent application Ser. No. 336,505, filed Jan. 8, 1964, an assigned to the assignee of the present invention.

According to present day color television standards in force in the United States an image to be projected by a television system is scanned horizontally once every $\frac{1}{15735}$ of a second by a light-to-electrical signal converter, and vertically at a rate of one field of alternate lines every one-sixtieth of a second. Correspondingly, an electron beam of a light producing or controlling device is caused to move at a horizontal scan frequency of 15,735 cycles per second in synchronism with the scanning of the light converter, and to form thereby images of light varying in intensity in accordance with the brightness of the image to be projected. The pattern of scanning lines, as well as the area of scan, is commonly referred to as the raster.

In FIGURE 2A is shown in schematic form a portion of such a raster in the light modulating medium along with the diffraction grating corresponding to the red color com-

ponent. The size of the raster or whole area scanned in the embodiment is approximately 0.82 of an inch in height, and 1.10 of an inch in width. The horizontal dash lines 33 are the alternate scanning lines of the raster appearing in one of the two fields of a frame. The spaced vertically oriented dotted lines 34 on each of the raster lines, i.e., extending across the raster lines schematically represent concentrations of charge laid down by an electron beam to form the red diffraction grating in a manner to be described hereinafter, such concentrations occurring at equally spaced intervals on each line, corresponding parts of each scanning line having similar concentrations thereby forming a series of lines of charge equally spaced from adjacent lines which cause the formation of valleys in the light modulating medium, the depth of such valleys, of course, depending upon the concentration of charge. Such a wave is produced by a signal superimposed on an electron beam moving horizontally at a frequency 15,735 cycles per second, a carrier wave, of smaller amplitude but of fixed frequency of the order of 16 megacycles per second thereby producing a line-to-line spacing in the grating of approximately $1/760$ of an inch. The high frequency carrier wave causes a velocity modulation of the beam thereby causing the beam to move in steps, and hence to lay down the pattern of charge schematically depicted in this figure with each valley extending in the vertical direction and adjacent valleys being spaced apart by a distance determined by the carrier frequency as shown in greater detail in FIGURE 2B which is a side view of FIGURE 2A.

In FIGURE 2C is shown a section of the raster on which a blue diffraction grating has been formed. As in the case of the red diffraction grating, the vertically oriented dotted lines 35 of each of the electron beam scan lines 33 represent concentrations of charge laid down by the electron beam. The grating line to line spacing is uniform, and the amplitude thereof varies in accordance with the amount of charge present. The blue grating is formed in a manner similar to the manner of formation of the red grating, i.e., a carrier frequency of amplitude smaller than the horizontal deflection wave is applied to produce a velocity modulating in the horizontal direction of the electron beam, at that frequency rate, thereby to lay down charges on each line that are uniformly spaced with the line to line spacing being a function of the frequency. A suitable frequency is nominally 12 megacycles per second. In FIGURE 2D is shown a side view of the section of the light modulating medium showing the deformations produced in the medium in response to the aforementioned lines of charge.

In FIGURE 2E is shown a section of the raster of the light modulating medium on which the green diffraction grating has been formed. In this figure are shown the alternate scanning lines 33 of a frame or adjacent lines of a field. On each side of the scanning lines are shown dotted lines 36 schematically representing concentrations of charge extending in the direction of the scanning lines to form a diffraction grating having lines or valleys extending in the horizontal direction. The green diffraction grating is controlled by modulating the electron scanning beam at very high frequency, nominally 48 megacycles in the vertical direction, i.e., perpendicular to the direction of the lines, to produce a uniform spreading out or smearing of the charge transverse to the scanning direction of the beam, the amplitude of the smear in such direction varying proportionately with the amplitude of the high frequency carrier signal, which amplitude varies inversely with the amplitude of the green video signal. The frequency chosen is higher than either the red or blue carrier frequency to avoid the undesired interaction with signals of other frequencies of the system including the video signals and the red and blue carrier waves, as will be more fully explained below. With low modulation of the carrier wave more charge is concentrated in a line along the center of the

scanning direction than with high modulation thereby producing a greater deformation in the light modulating medium at that part of the line. In short, the natural grating formed by the focussed beam represents maximum green modulation or light field, and the defocussing by the high frequency modulation deteriorates or smears such grating in accordance with the amplitude of such modulation. For good dark field the grating is virtually wiped out. FIGURE 2F is a sectional view of the light modulating medium of FIGURE 2E showing the manner in which the concentrations of charge along the adjacent lines of a field function to deform the light modulating medium into a series of valleys and peaks representing a phase diffraction grating.

Thus FIGURE 2 depicts the manner in which a single electron beam scanning the raster area in the horizontal direction at spaced vertical intervals may be simultaneously modulated in velocity in the horizontal direction by two amplitude modulated carrier waves, both substantially higher in frequency than the scanning frequency, one substantially higher than the other, to produce a pair of superimposed vertically extending phase diffraction gratings of fixed spacing thereon, and also may be modulated in the vertical direction by an amplitude modulated carrier wave to produce a third grating having lines of fixed line to line spacing extending in the horizontal direction orthogonal to the direction of grating lines of the other two gratings. By amplitude modulating the three beam modulating signals corresponding point by point variations in the depth of the valleys or lines of the diffraction grating are produced. Thus by applying the three signals indicated, each simultaneously varying in amplitude in accordance with the intensities of a respective primary color component of the image to be projected, three primary diffraction gratings are formed, the point by point amplitude of which vary with the intensity of a respective color component.

As used in this specification with reference to the specific raster area of the light modulating medium, a point represents an area of the order of several square mils and corresponds to a picture element. For the faithful reproduction or rendition of a color picture element three characteristics of light in respect to the element need to be reproduced, namely, luminance, hue, and saturation. Luminance is brightness, hue is color, and saturation is fullness of the color. It has been found that in general a system such as the kind under consideration herein that one grating line is adequate to function for proper control of the luminance characteristic of a picture element in the projected image and that about three to four lines are a minimum for the proper control of hue and saturation characteristics of a picture element.

Phase diffraction gratings have the property of deviating light incident thereon, the angular extent of the deviation being a function of the line to line spacing of the grating and also of the wavelength of light. For a particular wavelength a large line to line spacing would produce less deviation than a small line to line spacing. Also for a particular line to line spacing short wavelengths of light are deviated less than long wavelengths of light. Phase diffraction gratings also have the property of transmitting deviated light in varying amplitude in response to the amplitude or depth of the lines or valleys of the grating. Accordingly it is seen that the phase diffraction grating is useful for the point by point control of the intensity of the color components in a beam of light. The line to line spacing of a grating controls the deviation, and hence color component selection, and the amplitude of the grating controls the intensity of such component. In the specific system under consideration herein substantially the first and second diffraction orders of light are utilized in the red and blue primary color channels, and the first and third diffraction orders of light are used in the green primary color channel. The manner in which the instantaneous efficiency of the first,

second and third orders vary with depth of deformation, and also the manner in which the sums of the various ones of the orders varies with depth of deformation are described in connection with FIGURES 6 and 7. The manner in which the average efficiency for combination of various ones of the first, second and third orders varies with depth of deformation will be described in detail in connection with FIGURE 8.

Referring again to FIGURE 1, an electron writing system is provided for producing the phase diffraction gratings in the light modulating medium, and comprises an evacuated enclosure 40 in which are included an electron beam device 11 having a cathode (not shown), a control electrode (not shown), and a first anode (not shown), a pair of vertical deflection plates 41, a pair of horizontal deflection plates 42, a set of vertical focus and deflection electrodes 43, a set of horizontal focus and deflection electrodes 44, and the light modulating medium 10. The cathode, control electrode, and first anode along with the transparent target electrode 48 supporting the light modulating medium 10 are energized from a source 46 to produce in the evacuated enclosure an electron beam that at that point of focussing of the light modulating medium is of small dimensions (of the order of a mil), and of low current (a few microamperes), and high voltage (about 8 kilovolts). Electrodes 41 and 42, connected to ground through respective high impedances 68a, 68b, 68c, and 68d provide a deflection and focus function, but are less sensitive to applied deflection voltages than electrodes 43 and 44. The electrodes 43 and 44 control both the focus and deflection of the electron beam in the light modulating medium in a manner to be more fully explained below.

A pair of carrier waves which produce the red and blue gratings, in addition to the horizontal deflection voltage are applied to the horizontal deflection plates 42. The electron beam, as previously mentioned, is deflected in steps separated by distances in the light modulating medium which are a function of the grating spacing of the desired red and blue diffraction gratings. The period of hesitation at each step is a function of the amplitude of the applied signal corresponding to the red and blue video signals. A high frequency carrier wave modulated by the green video signal, in addition to the vertical sweep voltage, is applied to the vertical deflection plates 41 to spread the beam out in accordance with the amplitude of the green video signal as explained above. The viscous light modulating medium 10 is supported on transparent member 45 coated with a transparent conductive layer 48 adjacent the medium such as indium oxide. The viscosity and other properties of the light modulating medium are selected such that the deposited charges produce the desired deformations in the surface and such that the amplitude of the deformations decay to a small value after each field of scan thereby permitting alternate variations in amplitude of the diffraction grating at the sixty cycle per second field scanning rate to be described in greater detail in connection with FIGURE 9. The conductive layer is maintained at ground potential and constitutes the target electrode for the electron writing system. Of course, in accordance with television practice the control electrode is also energized after each horizontal and vertical scan of the electron beam by a blanking signal obtained from a conventional blanking circuit (not shown).

As the light modulating fluid 10 is subject to constant bombardment by the electron beam 12 with resultant deteriorations and alteration of the properties, physical and electrical, thereof a means is provided for moving new fluid into the active area of the system. To this end the disk 45 is supported on its axis by axle 100 which is also conductively connected to the transparent coating 48. The axle rests on a pair of bearings 101 and 102 located, respectively, in the side wall 103 of the enclosure and internal partition 104 of the enclosure 40. In the enclosure 40 conductive connection between the transparent coating 48 and the external circuit is made through the

axle 100. The partition 104 in cooperation with the outer wall 103 provides a retainer or reservoir for the viscous light modulating fluid 10. As the disk 45 is rotated it picks up the viscous light modulating fluid from the reservoir and by adhesion is retained thereon until it reaches the raster area where its thickness is further controlled by forces exerted thereon by charge deposited by the electron beam 12. Patent 3,155,871, William E. Good and Thomas T. True, assigned to the assignee of the present invention discloses details of such an arrangement. Of course, if desired, the thickness of the medium could also be controlled by mechanical knife edges, for example such as shown in U.S. Patent 2,776,339. The desired rotation of the disk may be accomplished by mechanical means such as motor 105 which may be included in the enclosure 40 and mechanically coupled to the disk 45 through a gear 106 which engages mating teeth in the periphery of the disk 45. Suitable circuits 107 are provided for energizing and controlling the speed of the motor to obtain the proper speed of rotation to the disk. A typical disk speed may be of the order of two revolutions per hour.

Above the evacuated enclosure 40 are shown in functional blocks the source of the horizontal deflection and beam modulating voltages which are applied to the horizontal deflection plates to produce the desired horizontal deflection. This portion of the system comprises a source of red video signal 50, and a source of blue video signal 51 each corresponding, respectively, to the intensity of the respective primary color component in a television image to be projected. The red video signal from the source 50 and a carrier wave from the red grating frequency source 52 are applied to the red modulator 53 which produces an output in which the carrier wave is modulated by the red video signal. Similarly, the blue video signal from source 51 and carrier wave from the blue grating frequency source 54 is applied to the blue modulator 55 which develops an output in which the blue video signal amplitude modulates the carrier wave. Each of the amplitude modulated red and blue carrier waves are applied to an adder 56 the output of which is applied to a push-pull amplifier 57. The output of the amplifier 57 is applied to the horizontal plates 44. The output of the horizontal deflection sawtooth source 58 is also applied to plates 44 and to plates 42 through capacitors 49a and 49b.

Below the evacuated enclosure 40 are shown in block form the circuits of the vertical deflection and beam modulation voltages which are applied to the vertical deflection plates to produce the desired vertical deflection. This portion of the system comprises a source of green video signal 60, a green grating or wobbling frequency source 61 providing high frequency carrier energy, and a modulator 62 to which the green video signal and carrier signal are applied. An output wave is obtained from the modulator having a carrier frequency equal to the carrier frequency of the green grating frequency source and an amplitude varying inversely with the amplitude of the green video signal. The modulated carrier wave and the output from the vertical deflection source 63 are applied to a conventional push-pull amplifier 64, the output of which is applied to vertical plates 43 to produce deflection of the electron beam in the manner previously indicated. The output of the vertical deflection sawtooth source 63 is also applied to the plates 43 and to plates 41 through capacitors 49c and 49d.

A circuit for accomplishing the deflection and focusing functions described above in conjunction with the deflection and focusing electrode system comprising two sets of four electrodes such as shown in FIGURE 1 is shown and described in a copending patent application Ser. No. 335,117, filed Jan. 2, 1964, and assigned to the assignee of the present invention. An alternative electrode system and associated circuit for accomplishing the deflection and focusing function is described in the aforementioned copending patent application, Ser. No. 343,990.

As mentioned above the red and blue channels make use of the vertical slots and bars and the green channel makes use of the horizontal slots and bars. The width of the slots and bars, in one arrangement or array is one set of values and the width of the slots and bars in the other arrangement is another set of values. The raster area of the modulating medium may be rectangular in shape and has a ratio of height to width or aspect ratio of three to four in accordance with television standards in force in the United States. The center-to-center spacing of slots in the horizontal array is made three-fourths the center-to-center spacing of the slots in the vertical array. Each of the lenticles in each of the lenticular plates are also so proportioned, i.e., with height to width ratio of three to four. The lenticles in each plate are stacked into horizontal rows and vertical columns. Each of the lenticles in one plate are of one focal length and each of the lenticles on the other plate are of another focal length. The filter element may be constituted to have three sections registering light of red and blue color components in the central portion of the input mask and green light in the side sector portions as will be apparent from considering FIGURE 3.

In FIGURE 3 is shown a view of the face of the second lenticular lens plate and input mask 28 as seen from the raster area of the modulating medium or along section 3-3 of FIGURE 1. In this figure the vertical oriented slots 70 are utilized in the controlling of the red and blue light color components in the image to be projected. The horizontally extending slots 71 located in the sector area in the input mask on each side of the central portion thereof function to cooperate with the light modulating medium and light output mask to control the green color component in the image to be projected. The ratio of the center-to-center spacing of the horizontal slots 71 to the center-to-center spacing of the vertical slots 70 is three-fourths. The rectangular areas enclosed by the vertical and horizontal dash lines 72 and 73 are the boundaries for the individual lenticles appearing on the opposite face of the plate 28. The focal length of each of the lenticles is the same. The center of each of the lenticles lies in the center of an element of a corresponding slot.

FIGURE 4 shows the first lenticular lens plate 27 taken along section 4-4 of FIGURE 1 with horizontal rows and vertical columns of lenticles 74. Each of the lenticles on this plate cooperates with a correspondingly positioned lenticule on the second lenticular lens plate shown in FIGURE 3 in the manner described above. Each of the lenticles on plate 27 have the same focal length which is different from the focal length of the lenticles on the second lenticular plate 28.

FIGURE 5 shows the light output mask 31 of FIGURE 1 taken along section 5-5 thereof. This mask consists of a plurality of transparent slots 75 and opaque bars 76 in a central vertically extending section of the mask and a plurality of transparent slots 77 and opaque bars 78 in each of two sectors of the spherical mask lying on each side of the central portion thereof. As mentioned previously the slots and bars from the output mask are in a predetermined relationship to the slots and bars of the input mask.

Referring now to FIGURE 6 there are shown graphs of the instantaneous conversion efficiency of the light diffracting grating formed in the light modulating medium as a function of the depth of modulation or deformation of the light modulating medium for various diffraction orders. In this figure instantaneous conversion efficiency for light directed on to the light modulating medium is plotted along the ordinate in percent and the deformation function Z, where

$$Z = 2\pi(n-1)\frac{h}{\lambda}$$

is plotted along the abscissa. In the above relationship h represents peak to peak amplitude or depth of de-

formation, λ represents the wavelength of light involved and n represents the refractive index of the light modulating medium. Graphs 80, 81, 82, and 83 show such relationships for the zero, the first, the second, and the third orders of diffracted light, respectively. In connection with this figure it is readily observed that when the light modulating medium is undeformed that all of the light is concentrated in the zero order which represents the undiffracted path of light. Of course, the light passing through the light modulating medium would be deviated slightly by refraction of the light modulating medium as normally the index of refraction of the light modulating medium is different from the index of refraction of vacuum or air surrounding the medium, and is conveniently selected to be approximately in the range of refraction indices of the material of the various vitreous optical elements utilized in the system. The output mask is positioned in relationship to the input mask such that when the light modulating medium is undeformed the slots of the input mask are imaged on the bars of the output mask and thus the slight refraction effects that occur are allowed for. As the depth of modulation for a given grating is increased, progressively more light appears in the various diffraction orders higher than the zero order. Typically the maximum depth of modulation is about 1.0 micron. Progressively as the peak efficiency of the first, second and higher orders of light is reached the value of the maximum efficiency of the higher order of light becomes progressively smaller. As can be readily seen from the graphs the maximum efficiencies of light in the first order, second and third orders is approximately 67 percent, 47 percent, and 37 percent, respectively.

In FIGURE 7 are shown graphs of the instantaneous conversion efficiency versus Z, the function of the depth of modulation set forth above, for various combinations of diffraction orders. In this figure instantaneous conversion efficiency is plotted in percent along the ordinate, and the parameter Z is plotted along the abscissa. Graph 85 shows the manner in which the instantaneous conversion efficiency of the first order increases when the depth of modulation reaches a peak of approximately 67 percent and thereafter declines. Graph 86 shows the manner in which the instantaneous conversion efficiency for the sum of the first and second orders of diffracted light increases reaching a peak at approximately 93% and thereafter declines. Similarly, graph 87 shows the manner in which the instantaneous conversion efficiency of the diffraction grating varies for the sum of the first and third orders increases reaches a peak at approximately 69% and thereafter declines. Finally, graph 88 shows the manner in which the instantaneous conversion efficiency of the sum of the first, second and third orders of light increases to a peak of approximately 98% and thereafter declines. Graph 89 shows instantaneous conversion efficiency of the sum of all orders except the zero order.

In FIGURE 8 are shown a group of graphs on the average conversion efficiency for the various combinations of diffraction orders as a function of the amplitude of deformation. The average conversion efficiency is represented in percent along the ordinate, and amplitude in terms of the aforementioned parameter Z is plotted along the abscissa. For the proper operation of the system of FIGURE 1 it is necessary for the light modulating medium to retain the diffraction deformations produced therein over a period comparable to the period of a scanning field. Ideally, each point of the light modulating medium should retain the deformation unattenuated until it is subject to a new deformation in response to the modulating signal. Practically, such an ideal situation cannot be met as the charge on the light modulating medium decays and thereby permits the diffraction patterns in the light modulating medium to decay. Under such practical conditions it is desirable for the deformations to decay to a small value over the period of a field of the television scanning process so that new deformation information can be applied to the

light modulating medium. The average efficiency graphs of FIGURE 8 are based on the decay of the deformations to approximately one-third their initial value over the period of a field. Accordingly, even after the electron charge has been deposited by the electron beam to produce the deformation the existence of the deformation continues to diffract the light incident on the medium. Graphs 90, 91, 92, and 93 show, respectively, the average efficiency of the first diffraction order, the sum of the first and second orders, the sum of the first and third orders, and the sum of the first, second and third orders.

Referring now to FIGURE 9 there is shown a graph 100 of the change in thickness or depth of the fluid layer due to differential charge on the fluid layer versus time in terms of the period of a field. The graph 100 represents the deformations produced by differential charge on an element of the fluid layer corresponding to a picture element. The graph has an exponentially rising portion 101 and an exponentially decaying portion 102. Also shown in the figure are graphs of the force function 103 of electron charge build up and decay on the surface of the layer. Such force function builds up rapidly and decays exponentially. The time it takes for the decay to fall to 37% of its peak value is referred to as the electrical time constant τ_e of the deformation. Also shown in this figure is a graph 104 of the mechanical build up in response to a set force function. After the application of a deforming force to the fluid layer it takes time for the fluid to conform to the condition required by such forces. The time it takes for the mechanical build up force function to rise to 63% of its peak value is referred to as the mechanical time constant τ_m of the deformation. The electrical time constant is a function principally of the conduction mechanism of the fluid. It has been found empirically that the electrical time constant varies directly with the square root of the product of viscosity and layer depth and inversely as the square root of electron beam current. It has also been found that mobility of the charge carriers involved in the conduction mechanism of charge decay on the surface varies in an inverse relationship to the viscosity of the layer. Mobility is defined as velocity of the charge carrier per unit of electric field strength. The mechanical time constant is dependent in principal part on the viscosity of the fluid layer, the depth of the fluid layer and the grating line density of which the deformation is a part. It has been found that as the viscosity of the layer is increased the mechanical time constant of the deformation is increased. It has been found that the mechanical time constant varies inversely as the cube of depth of the layer. It has been found in systems such as the system described in FIGURE 1 where the depth of layer is small in comparison to the line to line spacing of the diffraction gratings that the mechanical time constant of the deformation varies inversely as the fourth power of the grating line density. As the depth of fluid layer is increased to the point where it is comparable to the line to line spacing of the diffraction gratings, it has been found that the depth of layer has inappreciable effect on the mechanical time constant, and the mechanical time constant now varies inversely as the grating line density. The reason for such variation can be appreciated from the observation that in the case of grating lines of large spacing fluid moving in conformance to the forces set up therein has to move over relatively large distances. Such movement takes time, especially so, if resistance to such movement exists in the form of boundary forces associated with layers of small depth. The electrical decay is independent of line to line spacing of the gratings for depths which are small or even comparable to the line to line spacing of the gratings, i.e., as long as the predominant path of the conduction for surface charge is through the fluid to the substrate. The mechanical time constant is also a function of the surface tension of the fluid and its mass. While these properties are important in the deformation process they are not susceptible of sufficient variation to be useful in producing variations in

mechanical time constant as the three properties mentioned above, namely, the viscosity, depth and grating line density.

For the successful operation of the system of FIGURE 1 it is important that the sum of the mechanical and electrical time constants be of the order of a field of scan, i.e., the deformation should have decreased to about one-third of its peak value by the time the electron beam is ready to deposit another pattern of lines of charge at that point. The time of rise and fall of deformations associated with each of the gratings as well as the average value of such deformations during a field of scan should be more or less comparable to provide comparable average light transmission efficiency in each of the three primary color channels. It has been pointed out above that the mechanical time constants for the deformations associated with each of the three diffraction gratings of different line to line spacing are a function of line to line spacing, viscosity and depth of fluid. As the factors of viscosity and depth are the same for each of the three gratings, any difference in values of their mechanical time constants would result from difference in line to line spacing. The mechanical time constant of deformations associated with each of these gratings is a function of the reciprocal of the fourth power of the grating line density. Thus it is readily apparent that a problem is presented with regard to the maintenance of comparable rise and fall time for the deformations and the maintenance of proper average values of such deformations to provide comparable light transmission efficiencies in the gratings.

In each of FIGURES 10A, 10B, and 10C are shown a pair of graphs, one of which represents the rise and fall of deformations associated with the smallest line density grating of the system, and the other of which show the rise and fall associated with the greatest line density grating of the system for various proportionings of the electrical and mechanical time constants of the deformations. In FIGURE 10A graphs 105 and 106 represent the deformation time cycle for the lowest and highest density gratings, respectively. A long mechanical time constant is selected for the smallest line density or green grating, for example, by using a fluid of low viscosity and small depth or thickness and a correspondingly short electrical time constant is selected to provide good average light transmission efficiency in the green grating. Under such circumstances the mechanical time constant of the red diffraction grating 106 would be considerably smaller than that of the green diffraction grating, and as the electrical time constant is the same for both diffraction gratings the deformations associated with the red grating would decay to an inappreciable value well before the end of a field. Accordingly, the average light efficiency of the red grating represented by the area under the graph 106 would be unsatisfactory. The poor average light efficiency of the red grating of FIGURE 10A may be remedied by increasing the electrical time constant of the deformations as shown in FIGURE 10B wherein graphs 107 and 108 represent the deformation time cycles of the green and red gratings, respectively. When such is the case the red deformations do not decay to an inappreciable value until the end of a field thereby providing satisfactory red efficiency. Now, however, the decay of the deformations associated with the green diffraction grating as depicted in graph 107 extends well beyond the duration of a field and thus would interfere with deformations formed in the fluid layer in subsequent green fields. The problem of balancing light transmission efficiencies of low and high density gratings as depicted in FIGURES 10A and 10B is solved in accordance with the present invention by selecting the electrical time constant of the deformations, which are essentially the same for all three gratings, to be the predominant time constant. Preferably the electrical time constant is selected to be greater than $\frac{1}{16}$ of the duration of a field for the system described in connection with FIGURE 1, and the mechanical time

constant of the green or low line density grating is kept to a value less than $\frac{1}{10}$ of the period of a field. The general nature of the rise and decay of deformations associated with the low density grating and the high density grating for such electrical and mechanical time constants are shown in graph 109 and graph 110 of FIGURE 10C.

In connection with the diffraction grating formed by the raster lines of the system, in the illustrative embodiment the green diffraction grating of small line density, another problem is presented which arises from the requirement of interlace of scanning lines of alternate fields. In the system described the deformations associated with the green diffraction grating do not decay completely to zero value over the period of a field. In a succeeding field the lines of charge which produce the valleys of the deformations are deposited on what remains of the peaks of the deformations. Such action causes a cancellation of the image of the prior field and a build up of a new image. In certain cases, for example, when a light field follows a dark field wherein the fluid is relatively undeformed the differential charge, being of a magnitude to form not only valleys of desired average depth but also to overcome the residual prior deformation, now would displace fluid into positions of adjacent valleys. Such action is particularly noticeable at transitions in the projected image, i.e., at the edges of objects, and manifests itself not only as poor green resolution but also in the existence of green edges around objects, and the occurrence of green trailers associated with motion in the projected image. A measure of this limit is the cancellation ratio which is defined as the average groove or valley depth of the green grating without interlace for a particular system to the average groove or valley depth with interlace. A cancellation ratio of 2 to 1 is tolerable in the system. When the cancellation ratio becomes progressively greater than 3 to 1 the effects mentioned above become progressively greater and the resultant projected image becomes marginal. Also, with departures from perfect interlace, due to such causes as non-linearities in vertical sweep and variations in the vertical sweep of one field over the preceding field, the lines of successive fields move into a position where they are paired instead of interlaced. Such a condition produce green flashing which becomes more apparent and objectionable at higher cancellation ratios. Of course, if the deformations associated with the green grating were allowed to decrease to an inappreciable value such problem would not be presented. However, such an arrangement would not only result in impairment of overall light transmission efficiency but also balancing of the light transmission efficiencies of the various grating would be difficult if not impossible to achieve.

The requirements that the cancellation ratio be below a certain value signifies that the deformations of the green grating be reduced to less than a certain predetermined value at the end of each field. For a particular electrical time constant for the deformations this means that the mechanical time constant must be held to below a certain value. The graphs 115, 116, 117, 118, 119 of FIGURE 11 shows the locus of pairs of values of electrical and mechanical time constants for the deformations associated with the green diffraction grating for cancellation ratios of 1.5, 2, 3, 4, and 5, respectively. For example, when a time constant of $\frac{1}{10}$ of a field is utilized, to maintain a cancellation ratio of 2 to 1 the mechanical time constant of the deformations of the green diffraction grating should be less than $\frac{1}{10}$ of a field. If a higher cancellation ratio is tolerable, for example 3 to 1, then the time constant of the deformations of the green grating may be as high as $\frac{4}{10}$ of a field.

Referring now to FIGURE 12 there are shown a pair of graphs 120 and 121 of constant average light transmission efficiency of 75% and 60%, respectively, for the high line density or red grating of FIGURE 1 as a function of viscosity and fluid layer depth. Also shown

are a pair of graphs 122 and 123 of the mechanical time constant of the green diffraction grating as a function of viscosity and fluid layer thickness for values of $\frac{1}{10}$ and $\frac{2}{10}$ of a field, respectively. The graph 120 represents the constant average light transmission efficiency of the red diffraction grating in which the first and second orders of light are utilized, and in which the electrical time constant is equal to the duration of one field. The resultant light transmission efficiency of the grating is 75%. The graph 121 represents constant light transmission efficiency of the red diffraction grating in which first and second order of diffracted light are utilized and in which the electrical time constant is $\frac{1}{10}$ of a field. The resultant light transmission efficiency under such conditions is 60%. Graph 124 of FIGURE 12 represents the locus of values of viscosity and fluid depth which provide a 2 to 1 cancellation ratio. For the green diffraction grating the constant average light transmission graphs could have been plotted in place of the mechanical time constant for the conditions indicated, but as the factor of cancellation ratio is important for proper operation of interlaced systems the plotting of mechanical time constants as a function of viscosity and depth is more meaningful. In practice there is no difficulty in obtaining green writing efficiency at cancellation ratios up to two to one due to the available current density and coarseness of the grating.

Thus as the fluid layer is increased in thickness a lower viscosity may be used to provide the desired red average efficiency and enables higher viscosities to be used to provide good green average light transmission efficiency. While lowering the viscosity and increasing the thickness has the effect of reducing the mechanical time constant of the gratings, increased thickness will lead to increased electrical decay time with the net resultant that constant average efficiency is maintained. With the electrical time constant made substantially larger than the largest mechanical time constant and the sum of the two time constants made comparable to the duration of a field, balanced light efficiencies are obtainable.

The manner of utilizing the graphs of FIGURE 12 for selecting viscosity and larger depth to provide good performance in the high and low line density channels will be illustrated in an example. Assume 60% red transmission efficiency with electrical time constant of $\frac{1}{10}$ of a field for the red diffraction grating is acceptable. If the requirement is set that the cancellation ratio be less than 2 to 1, a mechanical time constant of 0.26 of a field is acceptable. This corresponds to the point where the locus of an allowed values graph 124 intersects the 60% red efficiency graph 121. Accordingly, a system having a layer viscosity of 750 centistokes and a depth of 11 microns would provide not only a suitable balance in the light transmission efficiency of the red and green gratings but would also meet the requirements of a 2 to 1 cancellation ratio.

Of course, since the blue diffraction grating has a line to line spacing intermediate the line to line spacing of the green and red diffraction gratings the rise and decay of deformations associated with the blue grating would inherently be satisfactory to provide good performance.

It has been found that the electrical decay or electrical time constant varies in an inverse relationship with the mobility of the charge carriers in the fluid. Mobility as mentioned above is defined as velocity of the charge carrier per unit of field strength. With low mobility fluids the electrical decay is inherently longer for a particular viscosity, for example, in siloxane fluids, the mobility is lower than in the polybenzyl toluene fluids. Accordingly, longer electrical decay can be achieved at low viscosities thereby enabling balanced light transmission efficiency and the other requirement with respect to cancellation ratio to be achieved in thinner layers than with fluids having higher mobilities. In terms of the graphs of FIGURE

12 this means that graphs 120 and 121 would not rise as steeply as layer depth is decreased.

A number of fluids may be used in accordance with the present invention, for example, the polybenzyl fluids mentioned in patent application Ser. No. 335,151, now Patent No. 3,288,927, filed Jan. 2, 1964, and assigned to the assignee of the present invention have proved satisfactory in a system as the kind set forth in FIGURE 1. Other fluids, for example, the siloxanes and other hydrocarbons are also suitable for use in the system of FIGURE 1.

In general in systems such as shown in FIGURE 1 viscosities in the fluid under normal operating conditions have ranged from about 200 to about 4,000 centistokes. Thickness in the range of 5 microns to 20 microns have been used in such apparatus in various forms. Bulk resistivities ranging from about 10^{10} to 10^{14} ohm centimeters have been found suitable. Properties such as surface tension, dielectric constant, mass density, and the index of refraction for the above mentioned fluids having the following approximate values, indicating order of magnitude, have proved satisfactory in the operation of the system of FIGURE 1:

Surface tension	ergs/cm. ²	35
Dielectric constant		3
Index of refraction		1.55
Mass density	grm/cm. ³	1.0

It has been pointed out above in connection with FIGURE 9 that differential charge density on the surface of the fluid layer produces a deformation which rises exponentially and thereafter decays and that such differential charge distribution over the entire area of the fluid layer form the three diffraction gratings which control element by element the amount of light of each of the three primary color components in the projected image. We have found that in a fluid layer constituted of a material such as, for example, a siloxane, a polybenzyl toluene or polybenzyl benzene, of large thickness and operated under large beam currents unwanted surface deformations unrelated to the desired intelligence in the form of deformation written on the fluid layer by the electron beam is produced.

We have found that for a given current if the depth of the fluid layer is reduced sufficiently such unwanted deformations are reduced so as to be imperceptible and have virtually no effect on the desired mode of operation of the system. We have also found that for a given depth of a fluid layer if the beam current, and hence the net charge accumulated on the surface or adjacent thereto by the deposition processes is reduced, that such unwanted deformations are also reduced to a point where they are not perceptible. Such depth for a given current is referred to as the critical depth or thickness. The mode of operation of the fluid layer with respect to such parameters as thickness and current at which such unwanted perturbations are formed is referred to as the noisy mode of operation and the mode of operation at which such perturbation do not appear is referred to as the quiet mode of operation.

The graph 136 of FIGURE 13 represents the variation of critical thickness of the fluid layer versus electron beam current density at the raster area for a phenyl-dimethyl chain-stopped methyl phenyl siloxane fluid. The electron beam voltage was approximately 8 kilovolts. At room temperature the fluid had a viscosity of about 1000 centistokes, and at operating temperature of approximately 35° C., the viscosity of the fluid was estimated at about 400 centistokes. The bulk resistivity of the fluid at room temperature was in the vicinity of 10^{12} to 10^{13} ohm cm. The area to the left of and below the graph represents the quiet mode of operation, and the area to the right of and above the graph represents the noisy mode of operation. It was found that at high viscosities, i.e., at lower operating temperature that the critical thickness for a given beam current was less than for lower viscosity fluids, i.e.,

as the viscosity was increased the graph of critical thickness versus electron beam current moved toward the zero axis, and conversely, as the viscosity was decreased the graph moved away from the zero axis.

Referring now to FIGURE 14 there are shown graphs of critical thickness of the fluid layer versus electron beam current density for a polybenzyl toluene fluid. The data on which these graphs are based were taken on apparatus such as that of FIGURE 1 which provided an electron beam voltage of 8 kilovolts. Graphs 137, 138, and 139 represent the relationship at the various viscosities 2500, 1400, and 1100 centistokes, respectively.

Referring now to FIGURE 15 there are shown graphs of critical thickness versus beam current density at the raster for a polybenzyl benzene fluid. The data on which these graphs are based were taken on apparatus such as that of FIGURE 1 which provided an electron beam of 8 kilovolts. Graphs 140, 141, and 142 show the relationship of critical thickness to beam current for respective viscosities in centistokes of 4200, 2000, and 1300, respectively.

The graphs of FIGURES 13, 14, and 15 show that for fluids suitable for use in light valve projectors the relationship of critical thickness to electron beam current varies in an inverse relationship, that at low currents the critical thickness is relatively large and at high currents it is relatively low, and the steepness of decline of critical thickness with current from a given current varies from fluid to fluid. Also that critical thickness for a given current and comparable viscosity varies from fluid to fluid.

With the fluids indicated, the operating depths of the layer is in the range of 7 to 12 microns, and the maximum deformation from peak to valley corresponding to the value h in the graphs of FIGURES 6 through 8, in the fluid is of the order of one micron. As the actual size of an embodiment of the apparatus of FIGURE 1 is approximately twice the size indicated in the drawing, schlieren systems incorporated therein essentially involving the light modulating medium and the output masks with the bars and slots represent a very sensitive system and very minuscule deformations in the surface of the fluid deviate light incident on the output bars through the slots. Accordingly, it is essential to restrict any extraneous perturbations to values which are quite small in comparison to the desired deformations.

In the operation of the system of FIGURE 1 it is desirable to use fluids which are able to withstand the electron bombardment without deterioration in terms of the physical properties such as viscosity, and also fluids which do not evolve gas, such as carbon and hydrogen, which would be harmful to the electron beam generating and forming processes. In general, the smaller the currents utilized to produce the desired deformations the less would be such deleterious effects.

It will be apparent from the description above that to obtain good writing qualities in terms of adequate deformations in the three primary color gratings as well as appropriate rise and fall time thereof for good and balanced light transmission therethrough that it is desirable to use layers of relatively large depth. However, invariably the combination of thicknesses and currents selected for good writing quality result in the operation of the fluid in the noisy mode with resultant unacceptable performance of the system. The present invention is directed to the provision of a system such as the system of FIGURE 1 at which optimum writing qualities in the fluid layer are achieved without unwanted perturbations or random undulations. In essence it involves arranging the operation of the system utilizing a particular light valve fluid for which thickness of the fluid layer and beam current utilized in connection therewith is selected to be in quiet mode.

From a consideration of the energy or power flow process in the fluid layer in the operation of the system of FIGURE 1 some appreciation may be gained of the possible causes of the formation of unwanted perturba-

tions for large beam currents and larger fluid layer depth as well as the manner in which such unwanted perturbations are affected by changes in viscosity. Consider a fluid layer having a small depth or thickness and operated at low beam currents, i.e., operating in the quiet mode. Energy input from the electron beam into the layer is conveyed through the fluid to the supporting base plate by a certain conduction mechanism. Assume that the thickness remains unchanged but that the beam current is increased. It appears that as the current is increased the energy conduction mechanism becomes saturated at a certain point and now the excess energy input must be either dissipated in or conveyed through the fluid by another mechanism. The surface undulations, it is believed, represent a physical manifestation of the operation of such other energy conduction mechanism. The same result would occur if the energy input in the form of constant beam current were kept constant and the thickness were increased. Apparently such increase in thickness results in the saturation of the conduction mechanism at lower current densities. In either case there is a transference of momentum by charge carrier motion to the fluid which results in the formation of unwanted perturbations and undulations in the fluid. Expressed in other ways, the rate of energy input in excess of a certain value results in a thermodynamic phase change in the bulk which manifests itself as the unstable surface undulations. Another way of viewing the production of random undulations in the surface of the layer is in terms of a conversion of electrostatic energy into hydrodynamic energy. While such conversion mechanism may be responsible for producing desired deformations it is believed that some of such hydrodynamic energy manifests itself in the form of random fluctuations. It is also believed that as boundary forces become more significant in thin layers than in thick layers, they have greater inhibiting influence on the formation of the cellular structure in the fluid associated with the noisy mode than do thick layers.

While it would appear that increasing viscosity of the fluid would have a damping effect of the formation of unwanted deformations, and that decreasing viscosity would promote the formation of unwanted deformations it is believed that decreasing viscosity has an effect on the conduction mechanism in terms of increasing charge carrier mobility which elevates the current density and thickness at which the conduction mechanism associated with the quiet mode saturates.

While the invention has been described in specific embodiments, it will be appreciated that many modifications may be made by those skilled in the art, and we intend by the appended claims to cover all such modifications and changes as fall within the true spirit and scope of the invention.

What we claim as new and desire to secure by Letters Patent of the United States is:

1. A projection system comprising:
a thin layer of light modulating fluid having a pair of opposed surfaces,
a conducting plane supporting one of said opposed surfaces,
means for producing an electron beam and directing said beam on an area of the other surface of said layer,
means for scanning said electron beam over said surface area,
conduction through said layer being sufficiently low to permit build up of charge in said fluid,
means for modulating said electron beam to produce a pattern of charge in said area varying in density thereover,
said charge in cooperation with said conducting plane producing deformations in the surface of said layer in accordance with the distribution of charge thereon,

said deformations decaying in accordance with the decay of charge through said layer,
the fluid in said layer having two phases, one in which the surface deformations are in accordance with the differential charge distribution on said surface and the other in which the surface has a random structure essentially unrelated to the differential charge and occurring above a predetermined average charge density for a predetermined depth of said layer, the average charge density at which said other phase occurs varying in an inverse relationship to the thickness of said layer,
means for maintaining said average current density and depth at values at which said one phase occurs, a light optical system for projecting light as a function of the deformations in said surface area of said fluid.

2. A projection system comprising:
a thin layer of light modulating fluid having a pair of opposed surfaces,
a conducting plane supporting one of said opposed surfaces,
means for producing an electron beam and directing said beam on an area of the other surface of said layer,
means for scanning said electron beam over said surface area,
the conduction through said layer being sufficiently low to permit build up of charge in said fluid,
means for modulating said electron beam to produce a pattern of charge in said area varying in density thereover,
said charge in cooperation with said conducting plane producing deformations in the surface of said layer in accordance with the distribution of charge thereon, said deformations decaying in accordance with the decay of charge through said layer,
the fluid in said layer having two phases, one in which the surface deformations are in accordance with the differential charge distribution on said surface and the other in which undulations appear in the surface essentially unrelated to the differential charge and occurring above a predetermined average charge density for a predetermined depth of said layer, the average charge density at which said other phase occurs varying in an inverse relationship to the thickness of said layer,
the average charge density at which said other phase occurs varying in an inverse relationship to the viscosity of said layer,
means for maintaining said average current density, and depth and viscosity at values at which said one phase occurs,
a light and optical system for projecting light as a function of the deformations in said surface area of said fluid.
3. A projection system comprising:
a thin layer of light modulating fluid having a pair of opposed surfaces,
a conducting plane for supporting one of said opposed surfaces,
means for producing an electron beam and directing said beam on an area of the other surface of said layer,
means for scanning said electron beam over said surface area,
conduction through said layer being sufficiently low to permit build up of charge in said fluid,
means for modulating said electron beam to produce a pattern of charge in said layer varying in density thereover,
said charge in cooperation with said conducting plane producing deformations in the surface of said layer in accordance with the distribution of charge thereon, said deformations decaying in accordance with the decay of charge through said layer,

said charge decaying through said fluid imparting momentum thereto, said momentum increasing with increasing depth of said layer and with increasing average charge density on said surface, means for maintaining the depth of said layer and the average charge density on said surface thereof below a predetermined value at which the decay of said charge through said layer is below a value which results in the formation of random deformations in said surface appreciable in amplitude in relationship to the deformations produced by said patterns of electron charge, 5 a light and optical system for projecting light as a function of the deformations in said surface area of said fluid. 15

4. A projection system comprising:

a thin layer of light modulating fluid having a pair of opposed surfaces, 20

a conducting plane supporting one of said opposed surfaces, means for producing an electron beam and directing said beam on an area of the other surface of said layer, 25

means for scanning said electron beam over said surface area, 25

conduction through said layer being sufficiently low to permit build up of charge in said layer, 30

means for modulating said electron beam to produce a pattern of charge in said layer varying in density thereover, 30

said charge in cooperation with said conducting plane producing deformations in the surface of said layer in accordance with the distribution of charge thereon, said deformations decaying in accordance with the decay of charge through said layer, 35

said charge in decaying through said fluid imparting momentum thereto, said momentum increasing with increasing depth of said layer and with increasing average charge density on said surface, 40

means for maintaining the current of said beam and the depth of said layer below a predetermined value to limit the conversion of electrostatic energy associated with the charge in said layer to hydrodynamic energy to a value inappreciable to produce random deformations in said surface, 45

a light and optical system for projecting light as a function of the deformations in said surface area of said fluid. 50

5. A projection system comprising:

a layer of light modulating fluid having a pair of opposed surfaces, 50

a conducting plane supporting one of said opposed surfaces, means for producing an electron beam and directing said beam on an area of the other surface of said layer, 55

means for periodically deflecting said electron beam over said area in one direction at a line frequency rate and in a direction orthogonal thereto at a field frequency rate, 60

the conduction through said layer being sufficiently low to permit the build up of charge on said area, means for modulating said electron beam to produce a pattern of lines of charge on said medium, each line being parallel to adjacent lines and uniformly spaced with respect thereto, 65

another means for modulating said electron beam for producing another pattern of lines of charge on said medium, each line being parallel to adjacent lines and uniformly spaced with respect thereto, 70

the line to line spacing of said one of said patterns being substantially different from the line to line spacing of said other pattern, 70

said lines of charge producing deformations in the surface of the layer in accordance with the differential 75

distribution of charge thereon, said deformations decaying in accordance with the decay of charge producing said deformations through said layer, the geometrical and physical properties of the fluid being proportioned such that the time of rise and the time of fall of deformations due to the differential charge on said area associated with each of said patterns is comparable to a field of scan and the time of fall is substantially greater than the time of rise of said deformations, a predetermined constant average light transmission efficiency of the gratings formed by said pattern of smaller line to line spacing occurring at a high value of viscosity and a low value of layer depth, said value of constant average light transmission efficiency being attained for decreasing viscosities by increasing depths, a predetermined constant average light transmission efficiency of the other grating formed by said other pattern of lines of charge occurring at a low value of viscosity and depth of said layer, said predetermined value of constant average light transmission efficiency increasing with increasing viscosity and increasing depth of said layer, the depth and viscosity of said layer being of values which simultaneously provide such predetermined constant average light transmission efficiencies for said gratings, the fluid in said layer having two phases, one in which the surface deformations are in accordance with the differential charge distribution on said surface and the other in which the surface has a random structure essentially unrelated to the differential charge and occurring above a predetermined average charge density for a predetermined depth of said layer, the average charge density at which said other phase occurs varying in an inverse relationship to the thickness of said layer, the average charge density produced by said electron beam being of a value at which said one phase occurs, a light and optical system for projecting light as a function of the deformations in said area of said fluid. 6. A projection system comprising:

a layer of light modulating fluid having a pair of opposed surfaces, a conducting plane supporting one of said opposed surfaces, means for producing an electron beam and directing said beam on an area of the other surface of said layer, means for periodically deflecting said electron beam over said area in one direction at a line frequency rate and in a direction orthogonal thereto at a field frequency rate, the lines of a pair of successive fields being interlaced, 60

the conduction through said layer being sufficiently low to permit the build up of charge on said area, means for modulating said electron beam to produce a pattern of lines of charge on said medium, each line being parallel to adjacent lines and uniformly spaced with respect thereto, another means for modulating said electron beam for producing another pattern of lines of charge on said medium, each line being parallel to adjacent lines and uniformly spaced with respect thereto, 70

the line to line spacing of said one of said patterns being substantially different from the line to line spacing of said other pattern, 70

said lines of charge producing deformations in the surface of the layer in accordance with the differential distribution of charge thereon, said deformations decaying in accordance with the decay of charge producing said deformations through said layer, the geometrical and physical properties of the fluid being proportioned such that the time of rise and the time of fall of deformations due to the differential charge on said area associated with each of said

patterns is comparable to a field of scan and the time of fall is substantially greater than the time of rise of said deformations,

- a predetermined constant average light transmission efficiency of the gratings formed by said pattern of smaller line to line spacing occurring at a high value of viscosity and a low value of layer depth, said value of constant average light transmission efficiency being attained for decreasing viscosities by increasing depths, a predetermined constant interlace cancellation ratio of the other grating formed by said other pattern of lines of charge varying with viscosity and depth of said layer, the depth and viscosity of said layer being of values which simultaneously provide said predetermined constant average light transmission efficiency for said one grating and said predetermined cancellation ratio for said other grating,
- the fluid in said layer having two phases, one in which the surface deformations are in accordance with the differential charge distribution on said surface and the other in which the surface has a random structure essentially unrelated to the differential charge and occurring above a predetermined average charge density for a predetermined depth of said layer, the average charge density at which said other phase
